UNITED STATES PATENT OFFICE.

DAVID B. COOK, OF FRANKFORT, NEW YORK, ASSIGNOR TO ACME ROAD MACHINERY COMPANY, OF FRANKFORT, NEW YORK, A CORPORATION OF NEW YORK.

SCARIFIER.

1,115,900.

Specification of Letters Patent.

Patented Nov. 3, 1914.

Original application filed August 29, 1912, Serial No. 717,810. Divided and this application filed June 30, 1913. Serial No. 776,731.

To all whom it may concern:

Be it known that I, DAVID B. COOK, of Frankfort, in the county of Herkimer, in the State of New York, have invented new 5 and useful Improvements in Scarifiers, of which the following, taken in connection with the accompanying drawings, is a full, clear, and exact description.

This invention relates to certain improvements in scarifiers adapted to be used more particularly in tearing up and loosening road beds or pavements preparatory to trenching, excavating, grading and resurfacing and similar operations which may be 10 necessary in road building or trenching for water pipes, sewers and other conduits which it may be desired to place under the road bed.

In most instances these road beds are 20 extremely hard and are difficult to penetrate and, under the method commonly used of plowing, the work is not only unusually expensive and laborious, but requires considerable power, and results in frequent 25 breakages of the apparatus employed and renders the use of mechanical motive power (which is preferable) impractical. Furthermore, it is frequently necessary to use apparatus of this character upon narrow 30 road beds or highways where it is impossible, or at least inconvenient, to turn the entire apparatus around for operation in reverse directions along such road bed.

The main object, therefore, of my present 35 invention is to render this scarifying operation more efficient and less laborious than has heretofore been practised and, at the same time, to permit the machine to be drawn or propelled from either end with a 40 minimum degree of motive power.

Another object is to provide the scarifier with forwardly converging rows of teeth disposed at an acute angle to each other, the teeth of opposite rows being spaced longitudinally substantially equal distances apart but transversely at gradually increasing distances from front to rear so as to cause them to travel in lines parallel with and at opposite sides of the center line of 50 draft thereby reducing and more evenly distributing the load or resistance offered by the entrance of the teeth into the road bed

and, at the same time, causing the machine to travel more easily along the separate line of draft with less liability of swerving to 55 right or left.

Other objects and uses relating to specific parts of the machine will be brought out in the following description.

Figure 1 is a perspective view of the detached scarifying implement or tooth-supporting frame except that the counter weight is removed. Fig. 2 is a horizontal sectional view through the front end of the scarifier taken on line 2—2, Fig. 1. Fig. 3 65 is a horizontal sectional view through one of the teeth and adjacent portion of the frame showing the fastening means for the tooth. Fig. 4 is a transverse vertical sectional view through one side of the scarifier 70 frame showing more particularly the guard rails and fastening means therefor. Fig. 5 is a longitudinal vertical sectional view through the center of the scarifier shown in Fig. 1. 75

This scarifying implement —2—, is adapted to be flexibly and reversibly mounted upon the underside of a main supporting frame as shown in my pending application No. 717,810 filed August 29, 1912, of which 80 this is a division and comprises a triangular frame of suitable length capable of being turned end for end between the wheels about a vertical axis and composed of opposite side bars or I-beams —24— of uniform length arranged at an acute angle with each other so as to diverge in substantially straight lines from one end toward the opposite ends, the latter being connected by a cross bar —25— as shown more clearly 85 in Figs. 1 and 5. This cross bar —25— which is rigidly secured to the adjacent ends of the said bars —24— serves the double purpose of bracing and holding said side bars a uniform distance apart and also 90 for receiving and supporting a suitable counterweight —26— for counter-balancing the scarifying implement upon its swivel or pivotal support presently described. The 95 opposite or converging ends of the said bars —24— are secured by bolts —27— to opposite faces of an intervening draw plate —28— having a series of bolt holes —29— for receiving a pivotal bolt —30— by which 100

the adjacent end of the scarifying implement may be attached to supporting bar —31—.

For convenience of further description, 5 the apex of the scarifier frame will be described as "the front end" while the opposite end will be termed "the rear end."

Secured to and between the front ends 10 of the side bars —24—, just at the rear of the draw-plate —28—, are a pair of horizontally disposed plates —32— and —33— having vertically inclined slots or openings therein for receiving a corresponding inclined master tooth —34—, the latter being 15 firmly held in operative position by a U-shape clip bolt —35— and a clip —36— which is drawn by the bolt —35— tightly against the rear edges of the plates —32— and —33— as shown more clearly in Figs. 20 2 and 5.

The outer flanges of each of the bars —24— are provided with a series of, in this instance six, vertically inclined recesses —37— for receiving a corresponding number 25 of similarly inclined cutter bars or teeth —34'—, which are fitted with an easy sliding fit in their respective recesses to firmly hold them against longitudinal movement on the side bars of the frame and are 30 additionally held in operative position by separate fastening devices consisting in this instance of clips —38— and bolts —39—, the latter passing through apertures in the adjacent portions of the webs of the side 35 bars —24— as shown more clearly in Fig. 4 and thereby permitting the teeth to be adjusted vertically to bring their points into the same horizontal plane and also to compensate for wear.

40 The main bodies or central portions of the teeth are preferably rectangular and elongated in cross section and are arranged edgewise vertically in planes substantially parallel with the longitudinal center of the 45 frame and, therefore, parallel with the line of draft so as to afford a maximum degree of rigidity in resisting the transverse strains to which the teeth may be subjected. The teeth —34'— are also spaced a uniform distance 50 apart longitudinally of the frame and, therefore, the transverse distance between the corresponding teeth at opposite sides gradually increase from front to rear so as to cause the teeth to travel in different paths 55 parallel with the longitudinal center of the frame and consequently with the line of draft as the machine is propelled over the road bed.

The front master tooth —34— is subjected 60 to the most severe initial strain by reason of the fact that it is first to enter the road bed and is, therefore, made somewhat heavier than the other teeth —34'— but all of the teeth are preferably made of hardened steel properly tempered to withstand 65

the strains to which they are subjected and are preferably of the same length and pointed at both ends so as to permit them to be reversed end for end when necessary or desirable. For example, in case the active 70 point of one tooth should break, said tooth may be easily removed and reversed end for end and re-clamped in place without appreciable loss of time or inconvenience.

All of the teeth are positioned at substantially 75 the same angle so as to incline downwardly and forwardly and their cutting edges are slightly curved toward the front of the frame and beveled transversely to produce a better cutting edge capable of 80 wedging itself more effectively into the road bed or pavement and at the same time exerting an uplift upon the loosened material as the machine is propelled.

A pair of rearwardly diverging guard- 85 rails —40—, consisting in this instance of angle-irons, are secured by bolts —41— and spacing sleeves —42— to the upper sides of and parallel with the side bars —24— so as to cover the upper pointed ends of the teeth 90 —34'— for the purpose of reducing the liability of injury to the operator or attendants, said guard-rails being also secured at their front ends to the draw plate —28—.

The scarifying implement is preferably 95 supported at a point near its center of gravity so that it may be easily turned or reversed end for end by hand about a vertical axis or tilted in any direction relatively to such axis in the manner hereinafter described and for this purpose I have provided the frame with a cross-bar —45— having its ends secured to the intermediate portions of the side bars —24— and to the central portion of this cross bar is secured an 100 upwardly projecting pivotal bolt —46— having an adjusting nut —47— which is swivelly connected to a hanger —48— on the underside of a superposed supporting frame (not shown).

The upper and lower flanges of the scarifier bars —24— are reinforced by lengthwise steel plates —80— riveted or otherwise secured thereto and are recessed in one side to correspond to the recesses —37— for receiving the teeth —34'— and additionally bracing them against relative movement longitudinal of the frame.

The nut —47— on the pivotal bolt —46— rests upon the upper surface of the hanger —48— and together with the bolt forms the main support for the scarifier about which the latter is adapted to turn end for end to cause the apex thereof to face either end of the machine according to the direction of 125 movement thereof although the front end of said scarifier is additionally supported by the link —31—.

What I claim is:

1. A road scarifier, including a frame- 130

work, a plurality of teeth carried thereby, and teeth-retaining bars connected to said frame-work above the same and serving to prevent the upward displacement of the 5 teeth.

2. A road scarifier, including a frame-work, a plurality of teeth carried thereby, and teeth-retaining bars connected to said frame-work and engaging the upper ends 10 of said teeth, for the purpose specified.

3. A road scarifier including a frame-work, a plurality of teeth carried thereby, and teeth-retaining bars of angular cross section connected to said frame-work and 15 preventing upward displacement of the teeth.

4. A scarifying implement including side bars angularly disposed with respect to the direction of movement of the implement, 20 upper and lower laterally extending flanges upon each side bar, a series of alined notches in said flanges, the notch of each series in

the upper flange disposed to the rear of the notch of the same series in the lower flange, the inner edges of the notched portions disposed in a plane substantially parallel with the direction in which the implement is adapted to move, scarifying teeth in said alined notches and means for holding said teeth in operative position. 25

5. A road scarifier including a frame-work, a plurality of teeth carried thereby, teeth retaining bars above the frame work and serving to prevent the upward displacement of the teeth, bolts connecting said bars 30 to said frame work, and spacing sleeves mounted on said bolts between the bars and the frame work.

In witness whereof, I have hereunto set my hand this 30th day of April, 1913.

DAVID B. COOK.
